UNITED STATES PATENT OFFICE.

ROBERT B. WOLF AND HARRY E. TIDMARSH, OF SANDY HILL, NEW YORK.

PAPER-MAKING MACHINERY.

No. 828,167.

Specification of Letters Patent

Patented Aug. 7, 1906.

Application filed November 10, 1905. Serial No. 286,670.

To all whom it may concern:

Be it known that we, ROBERT B. WOLF and HARRY E. TIDMARSH, citizens of the United States, residing at Sandy Hill, county of Washington, State of New York, have invented certain new and useful Improvements in Paper-Making Machinery; and we do hereby declare the following to be a full, clear, and exact description of the invention, such as will enable others skilled in the art to which it appertains to make and use the same.

The invention relates to paper-making machines, and more particularly to pulp-presses, wet-machines, and the like, and has for its objects to provide means for preventing leakage of stock from the stock-vat to the white-water chamber past the sleeve or sleeves with which the cylinder mold or screen is provided and through which the water drawn through the cylinder mold or screen passes to the white-water chamber.

In the accompanying drawings, which illustrate the application of the invention to the stock-vat and cylinder-mold of a wet-machine, Figure 1 is a plan view of the apparatus, part of the same being shown in section to better illustrate the invention. Fig. 2 is a longitudinal sectional view of the stock-vat, showing the cylinder-mold in elevation. Fig. 3 is a transverse section of a slightly modified form of mechanism. Fig. 4 is a front elevation of one of the collars or partitions which form the intermediate chamber, 35 showing a packing-ring applied thereto. Fig. 5 is an end elevation thereof.

In the particular embodiment of the invention illustrated in the drawings, N represents the stock-vat of a standard wet-machine, 40 which is adapted to receive the ground wood-pulp, sulfite-pulp, or paper-pulp admixed with large quantities of water and to deliver the pulp largely freed from the water to the "felt" R, which runs in contact with the surface of the cylinder-mold A, and thence over the couch-roll O, as will be understood by those skilled in the art. It is desired to have the white water, which passes through the wire-cloth with which the cylinder-mold is 45 covered, free from pulp or paper fibers, as large quantities of it cannot be used over again, and the fibers it holds in suspension are in consequence lost.

In machines of this general character it has 50 been attempted to prevent leakage between the stock-vat and the white-water chamber

by providing the end or ends of the cylinder-mold with a flanged offset which coöperates with a stationary ring on the end wall of the vat, which is usually covered with a felt ring, 60 thereby forming a telescoping joint. This in some measure prevents leakage past the end of the cylinder-mold into the adjacent white-water chamber. This arrangement, however, has not proved effective, as more or 65 less of the stock eventually works under the felt washer and through the telescoping joint into the white-water chamber. The essential object of the present invention is to obviate this leakage by providing an intermediate 70 chamber between the stock-vat and the white-water chamber, which effectively traps any leakage or seepage from either the stock-vat or the white-water chamber and prevents any admixture of the materials contained in the vat and chamber. In order to reduce leakage from the stock-vat to the intermediate chamber and also from the white-water chamber to the intermediate chamber to a minimum, suitable packing 75 means are provided between the collars which constitute the walls of the intermediate chamber and the sleeve of the cylinder-mold, through which the white water is discharged from the interior of the cylinder-mold 80 to the white-water chamber.

The vat N is formed within a rectangular tank built from any suitable material and is defined by the side walls and bottom of the tank and two transverse partitions located 90 intermediate the ends of the tank proper. Toward each end of the tank there is formed a white-water chamber M, said white-water chambers being adapted to receive the white water drawn through the meshes of the 95 screen-surface of the cylinder-mold by way of the hollow axial sleeves B. Each of the sleeves B at the point where it joins the head of the cylinder-mold is provided with an offset shoulder H, and at its end which projects 100 within the white-water chamber with an annular flange U, having an inturned rim which forms a peripheral edge substantially parallel with the cylindrical surface of shoulder H.

Between the stock-vat N and each of the 105 white-water chambers M is located an intermediate chamber J, which is defined by the extended side walls and bottom of the white-water chamber and two collars or partitions F and D, each of which is divided along a 110 horizontal line and is provided with a round opening to embrace the sleeve B, said collars

or partitions F and D forming the front and rear walls of the intermediate chamber aforesaid.

- The openings in the partitions F and D are 5 made somewhat larger than the diameter of the sleeve B, and suitable spacing-blocks B' are interposed between the surface of the sleeve and the interior walls of the openings aforesaid to provide a series of free channels 10 along the sleeve into the intermediate chamber J. The collars or partitions F and D are preferably made of wood or other suitable material, and the sections of each are fastened together around the sleeve B, so that the 15 collars or partitions may be removed and inserted with the cylinder. Each of the collars F and D is held against suitable guides or cleats T by any suitable means—such, for example, as a spreading device or wedge—so 20 that when the cylinder is in place leakage past the edge of the collars or partitions is prevented.

- Fitted between the collar D and the end face of the shoulder H is an annular packing-ring E, which may, if desired, be made up of 25 a series of sections to completely fill the space between said shoulder and said wall and in a large measure prevent leakage of stock from vat N past the shoulder H. The opening in 30 the packing-ring E is made of substantially the same diameter as the opening through the collar or partition D, so as to give free passage to the intermediate passage J of any material that should leak through the joints 35 formed by the contacting face of the packing-ring E with the wall D or the shoulder H. In order to insure a still more effective sealing of the joint between the end of the cylinder-mold and the intermediate chamber J, 40 there is provided a packing-sleeve of felt which encircles and engages the peripheral edges of the packing-ring E and the shoulder H.

- To prevent leakage from the white-water 45 chamber M into the intermediate chamber J, there is provided an annular packing G, which is preferably fastened to the square collar or partition F in substantially the same manner that packing-ring E is secured 50 to collar or partition D. Said packing G is adapted to engage the edge of the flange U on the end of the sleeve B, so as to form a practically water-tight joint therewith, as will be apparent from Figs. 1 and 2. To render the 55 joint thus formed still more secure, a sleeve of felt O is slipped over the periphery of the packing G and the flange U, so as to overlie the joint between the same, and said sleeve O may be secured either to the packing G or 60 to the flange U, as desired.

The cylinder-mold is, as will be understood, built around the usual shaft, which is supported in bearings CC, which may be located either inside or outside the white-water chamber or 65 chambers M or in any other desired position.

Below the white-water chambers at the respective ends of the tank are formed chambers L L, into which the respective intermediate chambers J discharge, and said chambers L are preferably connected by a pipe, 70 spout, or other suitable outlet X to a stock-tank or other receptacle, from which the pulp may be again delivered into the stock-vat N. Connection between each of the chambers L and the stock-vat N may also be provided by 75 suitable passages between the respective chambers, which passages are controlled by valves Y. When said valves Y are opened, the material in stock-vat N will be drained into the lower chambers L and thence to 80 the stock-chest or other suitable receptacle. This draining of the stock-vat N becomes necessary at times for washing or for other purposes, and by taking the stock from said vat by way of the lower chambers L into the 85 stock-chest much of the waste which is occasioned by the present methods of emptying the vat on the floor under the machine is obviated.

With the arrangement of apparatus hereinbefore described it will be apparent that leakage of stock from the stock-vat into the white-water chamber, except in such small quantities as might pass through the wire-cloth of the cylinder-mold, is absolutely prevented, as any of the stock which may leak past the joint between the shoulder H, the packing-sleeve F, and packing-ring E is delivered to the intermediate chamber J, from which it escapes to the lower chamber L and 90 thence to the stock-chest, from which it is ultimately returned to the vat N. Likewise the white water is prevented from leaking into the intermediate chamber J by the interposition of the packing members O and G, so 95 that practically all the white water is delivered to the chambers M free from contamination and is conducted therefrom as needed.

It will be noted that the collars or partitions D are of less height than the side walls 100 of the stock-tank N, so as to constitute what is, in effect, a dam separating the intermediate chambers J from the stock-vat. In addition to the main object subserved by the intermediate chamber J—to wit, to provide an 105 effective trap for leakage from the stock-vat or from the white-water chamber—the intermediate chamber may also be employed as an overflow for the stock-vat N in case it is desired to raise the stock or pulp to a higher 110 level in said vat, either to stir up the stock or to raise the level sufficiently to prevent the sheet of pulp or paper from dropping off the felt R, which travels around the couch-roll O, or to cause the sheet to again follow the felt 115 after it has been separated therefrom or for any other reason which during the operation of the machine renders it necessary or desirable to raise the stock in the vat N above the level defined by the top edge of the collar or 120

partition D. The square collar or partition F is, however, carried as high as the top of the stock-vat in order to prevent any of the material in the latter from passing into the white-water chamber when the level of the stock is raised.

The intermediate or overflow chamber J may be drained either from the bottom or pulp and water may be allowed to remain at any desired level therein by means of an adjustable or a fixed overflow either inside of or outside of said chamber J. The overflow-chamber may also be supplied with water or liquid of any kind maintained under sufficient head to tend to force the liquid from said chamber into both the stock-vat N and white-water chamber M. By maintaining a higher pressure or head in the chamber J than is maintained in either the white-water chamber M or the stock-vat N leakage into the intermediate chamber is wholly obviated, and as a matter of course leakage of stock from the stock-vat into the white-water chamber is absolutely precluded.

While the invention has been shown and described as applied to both ends of the tank and cylinder mold, it will be apparent that in some cases it may be desirable to blank off one end of the mold, thereby dispensing with the arrangement of sleeve, packing-rings, intermediate chamber and white-water chamber at that end and applying the invention to the other end of the apparatus only. Furthermore, it will be understood that the details of construction and the relative arrangement of the parts may be varied without departing from the spirit of the invention. For example, instead of the particular packing means to prevent leakage into the intermediate chamber, as hereinbefore described, packing-glands or stuffing-boxes of the ordinary kind may be employed; also, instead of constructing the white-water chamber and intermediate chamber within the main tank these parts may be built upon or attached to the cylinder-vat proper.

In case the false bottom V is used, as shown in Fig. 3, the space between the same and the cylinder-mold A may be drained into the lower chamber L, as hereinbefore described in connection with the vat N, whenever it is found necessary either because of the cylinder blocking with thick stock or for other causes.

While the invention has been described with particular reference to the cylinder-mold of a wet-machine, it is to be understood that it is not limited to such application, as the intermediate chamber between the screen-vat and the chamber which receives the water after passing through the screen, as well as the particular packing means hereinbefore described, may be applied with like advantages to any apparatus of this general character—such, for example, as water-screens, pulp-reducers, and the like.

What we claim is—

1. The combination of a stock-vat, a cylinder-mold therein, a white-water chamber in communication with the interior of the cylinder-mold, and an intermediate chamber between the stock-vat and the white-water chamber to prevent leakage between said vat and chamber. 70

2. The combination of a stock-vat, a cylinder-mold having an axial sleeve, a white-water chamber communicating with the interior of the cylinder-mold by way of said sleeve, and an intermediate chamber between the vat and the white-water chamber, said sleeve passing through said intermediate chamber. 75 80

3. The combination of a stock-vat, a cylinder-mold having an axial sleeve, a white-water chamber communicating with the interior of the cylinder-mold by way of said sleeve, an intermediate chamber between the vat and the white-water chamber, and packing between the wall of the intermediate chamber and the sleeve. 85

4. The combination of a stock-vat, a cylinder-mold having an axial sleeve, a white-water chamber communicating with the interior of the cylinder-mold by way of said sleeve, an intermediate chamber between the vat and the white-water chamber, and packings between the walls of the intermediate chamber and the sleeve to prevent leakage from the vat and white-water chamber respectively into the intermediate or overflow chamber. 90 95

5. The combination of a stock-vat, a cylinder-mold therein having an axial sleeve and a shoulder between the sleeve and the cylinder end, a white-water chamber communicating with the interior of the cylinder-mold by way of said sleeve, an intermediate chamber between the vat and white-water chamber, and a packing collar or washer surrounding said sleeve and engaging the wall of the intermediate chamber and the shoulder of the cylinder respectively. 100 105 110

6. The combination of a stock-vat, a cylinder-mold therein having an axial sleeve and a shoulder between the sleeve and the cylinder end, a white-water chamber communicating with the interior of the cylinder-mold by way of said sleeve, an intermediate chamber between the vat and white-water chamber, a packing collar or washer surrounding said sleeve and engaging the wall of the intermediate chamber and the shoulder of the cylinder respectively, and a packing-sleeve 115 120 125 engaging the packing-collar and shoulder of the cylinder respectively and overlying the joint between the two.

7. The combination of a stock-vat, a cylinder-mold having an axial sleeve provided with a shoulder at its junction with the cylinder and a flange at its outer end, a white-water chamber communicating with the interior of the cylinder by way of said sleeve, an 130

intermediate chamber between the vat and the white-water chamber through which said sleeve passes, and packing means interposed between the walls of the intermediate chamber and the shoulder and flange respectively of the sleeve.

8. The combination of a stock-vat, a cylinder-mold having an axial sleeve provided with a shoulder at its junction with the cylinder and a flange at its outer end, a white-water chamber communicating with the interior of the cylinder by way of said sleeve, an intermediate chamber between the vat and the white-water chamber through which said sleeve passes, packing-rings located between the walls of the intermediate chamber and the shoulder and flange respectively of the sleeve, and packing-sleeves closing the joints between the packing-rings and the shoulder and flange respectively.

9. The combination of a stock-vat, a cylinder-mold therein, a white-water chamber in communication with the cylinder-mold, an intermediate chamber between the stock-vat and the white-water chamber to receive any leakage from the stock-vat or the white-water chamber, and means for discharging the collected seepage from said intermediate chamber.

10. The combination of a stock-vat, a cylinder-mold therein, a white-water chamber in communication with the cylinder-mold, an intermediate chamber between the stock-vat and the white-water chamber to receive any leakage from the stock-vat or the white-water chamber, and a connection for said intermediate chamber to a stock-chest or other storage-receptacle.

11. The combination of a stock-vat, a cylinder-mold therein having an axial sleeve, a white-water chamber communicating with the interior of the cylinder-mold by way of said sleeve, and an intermediate chamber between the vat and the white-water chamber, the wall separating said intermediate chamber from the vat being lower than the vat sides to permit the stock to overflow into said chamber when the level of the stock is raised in said vat.

12. The combination of a stock-vat, a cyl-

inder-mold therein having an axial sleeve, a white-water chamber communicating with the interior of the cylinder-mold by way of said sleeve, an intermediate chamber between the vat and the white-water chamber, the wall separating said intermediate chamber from the vat being lower than the vat sides to permit the stock to overflow into said chamber when the level of the stock is raised in said vat, and means for conducting the stock from said intermediate chamber to a stock-chest or other receptacle.

13. The combination of a stock-vat, a cylinder-mold therein having an axial sleeve, a white-water chamber communicating with the interior of the cylinder-mold by way of said sleeve, an intermediate chamber between the vat and the white-water chamber, the wall between said intermediate chamber and the stock-vat being lower than the vat sides to permit the stock to overflow into said chamber when the level of the stock is raised in said vat, and packing means between the other wall of said intermediate chamber and the end of the axial sleeve to prevent leakage between the intermediate chamber and the white-water chamber.

14. The combination of a stock-vat, a cylinder-mold therein having an axial sleeve, a white-water chamber communicating with the interior of the cylinder-mold by way of said sleeve, an intermediate chamber between the vat and the white-water chamber, the wall between said intermediate chamber and the stock-vat being lower than the vat sides to permit the stock to overflow into said chamber when the level of the stock is raised in said vat, a packing-ring between the other wall of the intermediate chamber and the flanged end of the axial sleeve and a packing-sleeve embracing the peripheral edges of the packing-ring and flange.

In testimony whereof we affix our signatures in presence of two witnesses.
